RUFFLING ATTACHMENT FOR SEWING MACHINES

Alfred F. De Rose, Bridgeport, Conn.

Application April 6, 1949, Serial No. 85,929

7 Claims. (Cl. 112—134)

1

This invention relates to a ruffling attachment for sewing machines, and has for an object to provide an improved ruffling attachment which may be assembled complete as a unit and then attached as such to a sewing machine by simple attaching means without requiring reconstruction of the machine, and therefore the device may be applied complete by a simple operation to sewing machines already installed in a factory.

It is also an object to provide an improved construction for mounting the ruffler which will hold this device in a positive position regardless of the speed of the sewing machine.

A further object is to provide a device of this character with means whereby the movement or throw of the ruffler blade may be easily varied from no movement to maximum.

A particular object of the invention is to provide a ruffling attachment in which all the operating parts are located to the rear or in back of the presser foot of the sewing machine so that they do not obstruct the operator's view or annoy the operator with their movement, and thus there is nothing at any time to obstruct or interfere with a clear view of the operations involved, and there is also nothing to injure the operator.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

Fig. 1 is a front view of a sewing machine head showing my improved ruffling device attached thereto;

Fig. 2 is a top plan view thereof;

Fig. 3 is an end view looking from the right of Fig. 1;

Fig. 4 is an end view looking from the left of Fig. 1;

Fig. 5 is a detail side view of the ruffler blade support;

Fig. 6 is a view of the ruffler blade and support looking from the opposite side of Fig. 5;

Fig. 7 is a top plan view thereof, and

Fig. 8 is a front view of a portion of the machine head together with a section of the drive for the ruffling attachment from the main shaft.

The bed of the sewing machine is indicated at 10, and extending upwardly and above which is the head 11 in which is mounted the usual drive shaft 12 with any suitable means (not shown) for operating the needle bar 13 and the needle 14 carried thereby. Also mounted in this head is the usual presser foot 15 cooperating with the

2

usual feed 16 in the bed of the machine. The presser foot is mounted on the usual presser foot bar 17.

My improved ruffling attachment comprises a bracket 18 which is mounted on the upstanding portion 11a of the head 11 and is made in two sections 19 and 20 which are shaped to embrace the upright portion 11a of the head, and are secured together by any suitable means such as the screws 21 through ears or lugs 22 on these two sections on opposite sides of the section 11a. To securely secure the bracket to the head of the machine and to compensate for variations in the shape of this section 11a, the two sections 19 and 20 are provided with any suitable number of transversely extending set screws 23 which may be clamped against the walls of the portion 11a and securely mount this bracket on and clamp it to the machine head. These are preferably the countersunk type of set screws so as not to project from the bracket to form projections on which the cloth may catch. They with the bracket also provide means which effectively holds this bracket and therefore the whole ruffling attachment rigidly and effectively in position, and prevent its shifting during operation of the device at any speed of the sewing machine. The sections of the portion of this bracket embracing the machine head may be of any cross section desired, that shown being substantially T-shaped as it provides great strength for the amount of material used.

The rear section 19 includes a longitudinal bearing support 24 in which is mounted a tubular bearing or sleeve 25 for a ruffler shaft 26. The tube or sleeve 25 is of larger internal diameter than the shaft 26 and supports a pair of bearings 27 adjacent its opposite ends for this shaft. The sleeve 25 may be secured in the support 24 by any suitable means. Thus, it may be a tight or press fit, or it could be secured by a set screw (not shown). The sleeve 25 projects from the bearing 24, as shown in Figs. 1 and 2, to a position adjacent the needle bar, but it will be seen that it is located rearwardly of the head 11 and the needle bar and presser foot and extends longitudinally of this head at a proper distance above the bed 10. The outer end of the shaft 26 projects from the sleeve 25 and may be extended any desired distance as is found necessary or desirable for locating the ruffler blade at any position relative to the needle and the presser foot. There is a downwardly extending arm 28 secured to this shaft by any suitable means such, for example, as the set screw 29 and is forked at its lower end 30 for carrying a bar 31 which is pivoted to the arm 28 and the fork 30 at 32, and extends forwardly therefrom above the bed 10 to a position in front of the needle and presser foot where it carries the transverse stud 33 on

which is mounted the ruffling blade 34. This is a thin tempered steel blade provided with cloth gripping teeth 35 at its free edge and may be slotted as indicated at 36 to embrace the path of the needle. It is clamped on the rod 33 by the supporting head 37 and is clamped in any desired angular position on the bar 31 by the nut 38. This ruffler blade is also a spring blade so that it may yield upwardly on backward movement over the cloth and also to compensate for variations in the thickness of the cloth to be stitched and ruffled. The free end or tooth edge is directed rearwardly. The bar 31 is made in two sections 39 and 40 to permit adjustment of the position of the ruffler blade. In the particular form shown, the section 39 is of channel shape and the section 40 is flat bar mounted in the channel and provided with an elongated slot 41 through which clamping screws 42 mounted in the section 39 may extend for clamping the section 40 in different adjusted positions. The bar 31 also has a rearward extension 43 to which a tension spring 44 may be secured and also secured at its upper end to a rod 45 extending laterally from a lug 46 of a supporting collar 47 secured on the sleeve 25 by any suitable means, such, for example, as the set screw 48. Mounted on the presser foot bar 17 is a lifting means 49 comprising a rod having a lateral lower end portion 50 extending under the bar 31 so that on lifting of the presser foot this lifter 50 will also raise the forward end of the bar 31 and lift the ruffling blade from the work, to permit withdrawal of the work or adjusting of it to any position.

The shaft 26 is operated from some operative part of the machine, preferably from the shaft 12 in the sewing machine head by means of an eccentric cam 51 mounted on this shaft, and a connecting rod 52 leading from the eccentric housing 53 embracing the cam and connected to the upper end of a curved operating arm or lever 54 secured on the opposite end of the shaft 26 by any suitable means, such, for example, as the set screw 55. This prevents the shaft 26 shifting to the left as viewed in Figs. 1 and 2, and a stop collar 56 secured on the shaft at the other end of sleeve 25 by any suitable means, such as the set screw 57, prevents the shaft shifting in the opposite direction. The eccentric cam 51 may be secured directly to the shaft 12 but it is preferably secured to the usual hand wheel 58. Thus in mounting this connection the hand wheel may be removed from the shaft and the eccentric secured to the inner side thereof by any suitable means, such, for example, as the screws 59. Between the eccentric and the housing 53 is an antifriction or ball bearing 60 for quieter and more effective operation, and the connecting rod 52 is adjustable. This rod is threaded on its opposite ends, one of which is a right hand and the other a left hand thread. Thus, for example, the portion 61 may be a left hand thread threaded into the lug 62 on the housing 53 and secured in adjusted position by a lock nut 63. The other end 64 has a right hand thread and is threaded into a block 65 and secured in adjusted position by a lock nut 66. This block 65 has a spherical bearing for a ball 67 on the bolt 68 connecting this block to the lever arm 54 to thus provide a universal joint which will permit lateral or rocking movements as well as pivotal movements of the connecting rod 52 with respect to the lever arm 54, and thus prevent any binding or cramping action between the housing 53 and the lever 54 in operation of the device and assure smooth,

effective operation. For the purpose of adjusting the movement or throw of the ruffling blade the bolt 68 is adjustable along the arm 54. In the construction shown the arm 54 is provided with a longitudinal curved slot 69 in which the bolt 68 is mounted and in which it may be secured in adjusted positions by a clamping nut 70, or if desired this bolt may be shifted along the slot and therefore vary its distance from the operating shaft 26 by means of a hand or foot operated lever (not shown) by means of a rod 71 connected to a lug 72 on the block 65. A coil spring 73 may be connected to this lug 72 to tend to lift this block to the upper position, the spring being supported by any suitable means, such as an extension bar 74 mounted on the machine head.

The usual separator blade used with the ruffling blade is shown at 75 in front of the presser foot and is carried on an arm 76 pivoted at 77 to a supporting arm 78 mounted on the sleeve 25 by the head portion 79 embracing the sleeve and adjustably secured thereto by any suitable means, such, for example, as the set screws 80. Means is also provided for varying the angular position of the arm 76 and the blade, and in the form shown comprises a lug 81 on the arm carrying an adjusting screw 82 resting against a stop rib 83 on the arm.

It will be seen from the above that this ruffling device or attachment can be completely assembled as a unit on a bench or other location and secured to the sewing machine by removing the hand wheel 58 and securing the eccentric cam thereto, and then replacing this wheel on the shaft 12 and clamping the bracket 18 on the head of the machine as shown. The ruffling blade may be adjusted and located at proper positions by adjusting the arm 28 to the proper position on the operating shaft 26 and adjusting the blade support 40 in the section 39 of the rod 31. The angular position of the wheel 58 on the shaft 12 determines the timing of the device with relation to the needle and the feed. It is arranged so that as the needle point goes into the goods the ruffler blade moves forwardly with respect to the machine, which is the reverse or nonoperating movement of the blade. The blade ruffles the fabric as it moves in the same direction as the feed motion, or that is, rearwardly, but it ruffles it because it moves faster than the feed. When the connecting rod or arm 52 from the eccentric drive is at the top of the slot in the arm 54, there is very little, if any, movement to the ruffler blade, or at least the throw is at a minimum and the length of the ruffle or the throw of the blade is varied by shifting the connection 65 downwardly in the slot 69, the greatest movement of the blade being secured when this connection is in the lower end portion of this slot. It will be evident that with the device arranged as shown there is nothing in front of the needle or presser foot either to obstruct the view of the work or to interfere with the operation. Therefore, the operator has a clear view of the work and all operations at all times, and the movements of the operating mechanism cannot interfere with this work or distract her attention. Also there is nothing on which the operator can be injured. To prevent changing of the position of the ruffling blade with relation to the feed or needle when shifting the connection 65 in the slot 54, this change can be compensated for by the adjustment of rod 52. By loosening the nuts 63 and 66 the rod 52 may be changed to vary its effective length by means of the right and left hand

threads to compensate for variations due to shifting of the connections 65, and it can be secured in adjusted position by tightening the nuts 63 and 66. It will also be seen that the position of the arm 28 and therefore the blade can be adjusted either longitudinally or angularly on the shaft 26 by merely loosening the set screw 29, and this screw may be locked in clamped position by a lock nut 84 to prevent the possibility of the arm loosening up in operation. By this means the link or bar can be set in any desired position, either right or left of the needle, by simply shifting this arm on the shaft.

It will be understood different types of work feed blades may be used on this device for ruffling or other operations as found desirable, or feed teeth could be used for shirring or similar operations. The spring 44 and arrangement of arm 28 and bar 31 provide for varying degrees of tension of the ruffler blade or shirring feed teeth on different types of cloth. With this arrangement the spring provides an increasing tension as the blade moves forwardly in the direction of feed of the cloth, because the bar 31 swings counterclockwise about its pivot 32 as viewed in Fig. 4 on this motion, thus lengthening spring 44. This tension decreases on the reverse or backward motion. The tension of the spring 44 may be adjusted by shifting position of the bar 45 angularly about the sleeve 25.

Having thus set forth the nature of my invention, I claim:

1. A ruffling attachment for sewing machines comprising as an assembled unit and attachable to a sewing machine as such, a bracket, means for mounting the bracket on the head of the machine, said bracket including a bearing at the rear of said head, a shaft mounted in said bearing and extending horizontally to a position at the rear of the presser foot of the sewing machine, an arm mounted on said shaft, a bar pivoted to and extending forwardly from said arm to a position adjacent the presser foot, a work feed blade mounted on said bar, a lever arm mounted on the shaft, and means connecting said lever arm to an operative part of the sewing machine to oscillate said lever arm and shaft.

2. A ruffling attachment for sewing machines comprising a bracket, an oscillating shaft mounted in the bracket, means for securing the bracket to the head of a sewing machine to locate the shaft to the rear of the said head and to the rear of the presser foot of the machine, a depending arm carried by the shaft, a forwardly extending bar pivoted to said arm, a work feed blade mounted on said bar and located adjacent the presser foot, and means for oscillating said shaft connected to an operative part of the machine.

3. A ruffler attachment for sewing machines comprising a bracket, an oscillating shaft mounted in the bracket to extend horizontally to the rear of a sewing machine head, an arm secured to said shaft, a bar pivoted to and extending forwardly from said arm, a work feed blade carried by said bar adjacent the machine presser foot, an operating lever arm secured to the shaft, an eccentric crank, a bearing housing embracing said crank, an adjustable connection from said housing to the lever arm, an operative connection from the sewing machine to said crank to operate it, and means for securing said bracket to the sewing machine.

4. A ruffler attachment for sewing machines

comprising a bracket including separable curved parts to embrace the upright portion of a sewing machine head, means for clamping said parts about said portion to secure the bracket thereto, said bracket being provided with a horizontal bearing at the rear of said head, a horizontal shaft extending from said bearing to a position at the rear of the presser foot of the machine, a laterally extending arm mounted on the shaft, a bar pivoted to and extending forwardly from said arm, a work feed blade mounted on said bar adjacent the presser foot and directed rearwardly, and means connecting said shaft with an operative part of the machine to oscillate said shaft.

5. A ruffler attachment for sewing machines comprising a bracket, means for clamping the bracket about the upright portion of a sewing machine head, said bracket including a horizontal bearing at the rear of said head, a sleeve mounted in said bearing and projecting laterally therefrom, spaced bearings on the sleeve, a shaft mounted in said latter bearings and projecting from the free end of the sleeve, a depending arm mounted on the shaft, a forwardly extending bar pivoted to the lower end of the arm, a work feed blade mounted on the bar adjacent the machine presser foot and directed rearwardly, said bar being provided with a projection extending rearwardly of its pivot, a support on the sleeve, a coil spring connecting said extension to said support, and means connecting the shaft with an operative part of the machine to oscillate the shaft.

6. A ruffler attachment for sewing machines comprising a bracket, means for clamping the bracket to a sewing machine head, said bracket including a horizontal bearing at the rear of said head, a shaft mounted in said bearing and extending horizontally at the rear of said head to a position at the rear of the presser foot of said machine, a depending arm mounted on said shaft, a bar pivoted to and extending forwardly from the lower end of the arm, a work feed blade mounted on said bar adjacent the presser foot and directed rearwardly, a lever arm secured to the shaft, an eccentric crank, an adjustable driving connection from the crank to said lever arm including a ball and socket connection, said connection being movable along said lever arm toward and from the shaft to vary the throw of the work feed blade, and means for securing the crank to an operative part of the machine to operate the crank and oscillate the shaft.

7. A ruffler attachment for sewing machines comprising a bracket, means for clamping the bracket to a sewing machine head, said bracket including a horizontal bearing at the rear of said head, a shaft mounted in said bearing and extending horizontally at the rear of said head to a position at the rear of the presser foot of said machine, a depending arm mounted on said shaft, a bar pivoted to and extending forwardly from the lower end of the arm, a work feed blade mounted on said bar adjacent the presser foot and directed rearwardly, said bar comprising two sections, means securing said sections together for relative longitudinal adjustment and securing them in adjusted positions to vary the position of the blade, and means connecting the shaft to an operative part of the machine to oscillate the shaft and reciprocate the blade.
